UNITED STATES PATENT OFFICE.

JOHN B. VAN HOUTEN, OF NEWARK, NEW JERSEY.

DESIGN FOR AN EAR-RING PENDANT.

SPECIFICATION forming part of Design No. 14,864, dated March 4, 1884.

Application filed November 30, 1883. Term of patent 7 years.

To all whom it may concern:

Be it known that I, JOHN B. VAN HOUTEN, a citizen of the United States, residing at Newark, in the county of Essex and State of New Jersey, have invented and produced a new and original Design for Ear-Ring Pendants; and I do hereby declare the following to be a full, clear, and exact description of the invention, such as will enable others skilled in the art to which it appertains to make and use the same, reference being had to the accompanying drawings, and to letters of reference marked thereon, which form a part of this specification, in which—

• 15 Figure 1 is a front, and Fig. 2 an edge or a side view, of my newly-designed ear-ring. These two views fully illustrate my design.

The distinguishing feature of this design is in the peculiar form or configuration of the pendant, which is as follows: At the top where it is connected to the ear-wire are two scrolls, *a a*, reversed in relation to each other, beneath

which the outline of the pendant is irregular in form, being composed at each side of a square, *b*, a bead, *c*, and finishing at the bottom in the form of a half-diamond, *d*. Across the face of the pendant, in relief, near the center, is a square bar, *e*, encircled in the middle by a band, *f*, and at each end of the bar is a spherical projection, *g*, all as shown in the drawings.

The engraving or other ornamentation may be varied to suit the taste.

I claim—

The design for an ear-ring pendant herein shown and described.

In testimony that I claim the foregoing I have hereunto set my hand this 28th day of November, 1883.

JOHN B. VAN HOUTEN.

Witnesses:

OLIVER DRAKE,
CHARLES H. PELL.
